(57) CLAIM

The ornamental design for the ball, as shown and described.

DESCRIPTION

The present application is filed contemporaneously with the nonprovisional utility patent application, 11/121,214, entitled Method and Apparatus for Playing a Ball Game.

FIG. 1 is a perspective view of the design;

FIG. 2 is a front elevational view of the design;

FIG. 3 is a right side elevational view of the design;

FIG. 4 is a left side elevational view of the design;

FIG. 5 is a rear elevational view of the design;

FIG. 6 is a top plan view of the design; and,

FIG. 7 is a bottom plan view of the design.

The top and bottom end portions shown in broken lines are for illustrative purposes only and form no part of the claimed design.
